UNITED STATES PATENT OFFICE.

JOHN F. LEWIS, OF BRADDOCK, PENNSYLVANIA, ASSIGNOR, BY DIRECT AND MESNE ASSIGNMENTS, OF FIVE-SIXTHS TO MICHAEL KILLEEN, OF BRADDOCK, PENNSYLVANIA, AND ALBION P. AIKEN, OF PORT PERRY, PENNSYLVANIA.

FURNACE-CHARGING APPARATUS.

SPECIFICATION forming part of Letters Patent No. 729,877, dated June 2, 1903.

Application filed February 15, 1902. Serial No. 94,200. (No model.)

To all whom it may concern:

Be it known that I, JOHN F. LEWIS, of Braddock, Allegheny county, Pennsylvania, have invented a new and useful Furnace-Charging Apparatus, of which the following is a full, clear, and exact description, reference being had to the accompanying drawing, forming part of this specification, in which the figure is a vertical central section of a blast-furnace top provided with my improved device, the walls of the furnace being shown in dotted lines.

In the operation of blast-furnaces it is of the greatest importance that the charge should be evenly distributed properly within the furnace. If it is distributed improperly, especially if the fine material of the charge is permitted to accumulate next to the furnace-wall, it is apt to cake and to cause slips in the furnace, which are dangerous and interfere with the regularity of operation.

The purpose of my invention is to prevent the uneven distribution of the charge within the blast-furnace; and to this end it consists in combining with the charging bell and hopper of a furnace a skirt or deflector, which extends below the bell and preferably to a point above the lowest position of the bell and which will cause the material discharged from the bell to be deflected inwardly to some extent.

In the drawing, 2 is the charging-hopper of a furnace, and 3 is the bell, having a lifting-rod 4. The bell and hopper may be of any suitable construction. These parts are operated in the usual way, the charge being introduced into the hopper around the bell and then discharged into the furnace by lowering the bell.

5 is a skirt or deflector which extends downwardly below the bell and preferably terminating at a level above the lowest position thereof and near the stock-line of the furnace. This deflector is formed with sides which converge inwardly somewhat if the bell is of proportionately large size. If the bell is relatively small, the deflector may have vertical sides, or the sides may flare downwardly and outwardly. In each case the deflector is proportioned according to the size of the bell

and furnace-chamber. When the stock is discharged from the hopper by lowering the bell, it is directed outwardly by the inclined sides of the bell, but will strike the inner surface of the skirt and will thus be dropped 55 intermediately between the center and sides of the furnace-chamber, and the highest point of the charge will lie in the intermediate zone containing the finer portions. This distribution of the charge is the one most favorable to the proper operation of the furnace. By moving the bell below the lower end of the deflector I am enabled to discharge lumps which would otherwise become jammed between the bell and deflector.

The advantages of my invention result from the perfect distribution of stock and the preventing of hanging and slipping of the charge. A larger percentage of fine ores may be used, and the brickwork is protected. The gas-channels are kept open and back pressure greatly reduced. A saving of fuel is effected, and the invention can be easily applied to any style of furnace-top. The stock-line is of course kept below the level of the lower end of the 75 deflector.

Within the scope of my claim the deflector may converge either inwardly or outwardly, and other variations may be made in the form and arrangement of the deflector without departing from my invention.

I claim—

A blast-furnace having a charging-hopper with inwardly and downwardly converging sides, a bell arranged to close the lower end 85 of the hopper, an annular deflector supported on and extending down from the hopper within the furnace-chamber, said deflector having converging sides with an annular space between it and the furnace-stack, and 90 mechanism for moving the bell downwardly to a level below the lower end of the deflector to allow passage of lumps; substantially as described.

In testimony whereof I have hereunto set 95 my hand.

JNO. F. LEWIS.
